UNITED STATES PATENT OFFICE

JAMES TRACEY, OF BOONTON, NEW JERSEY

ROLLER SKATE

Application filed October 9, 1930. Serial No. 487,560.

This invention relates to skates and more particularly to a skate of the roller type in which a number of rollers are rotatably mounted in alined spaced relation to each other longitudinally of the skate.

One object of the invention is to provide a skate of this type wherein the rollers are rotatably mounted in an approved manner and so mounted that they are disposed in a common horizontal plane and all bear against the ground when the skate is in use.

Another object of the invention is to so mount the rollers that they will be almost entirely enclosed in a pocket formed in a depending portion or blade of the skate with only a very small portion of each roller projecting downwardly out of the pocket. By this arrangement the rollers will be braced against side play and prevented from being subjected to side strain.

Another object of the invention is to provide the rollers with improved bearings which may be very easily assembled and will cause the rollers to turn easily.

Another object of the invention is to provide the skate with a foot plate and depending roller-receiving portion or blade formed integral with the foot plate, thereby providing a skate which will be very strong and at the same time of a simple construction.

The invention is illustrated in the accompanying drawings, wherein

Figure 1 is a side elevation of the improved skate,

Fig. 2 is a bottom plan view thereof, and

Fig. 3 is a transverse sectional view taken on the line 3-3 of Fig. 1.

The foot plate 1 of the improved skate is preferably formed of cast metal, such as aluminum, or any other metal desired which is strong but at the same time light in weight. A depending portion or blade 2 is cast integral with the foot plate and extends longitudinally thereof midway its width. By referring to Figures 2 and 3, it will be seen that the blade is formed with a longitudinally extending pocket of substantially the full depth of the blade and open along its bottom. Side walls of the pocket are formed with openings 3 and 4 which are disposed in op-

posed relation to each other, and by referring to Figure 3 it will be seen that each opening 4 is unthreaded whereas its opposed opening 3 is of reduced diameter and threaded. Therefore, the axles 5 which are in the form of short bolts may be passed inwardly through the openings 4 and have their reduced and threaded ends 6 engaged in the threaded openings 3 and the bolts tightened by a suitable wrench until their heads 7 bear very tightly against the outer side face of the wall through which the openings 4 are formed. In view of the fact that the depending portion or blade is cast integral with the foot plate, the skates will be very strong and since the pocket has end walls connecting its side walls these side walls will be braced and prevented from easily breaking off. It should also be noted that openings 8 have been formed in the foot plate in order to reduce its weight.

The rollers 9 may be formed of steel or any other suitable material and while six have been shown, it will be understood that any number desired may be provided. These rollers are fitted into the pocket in spaced relation to each other longitudinally thereof and since the blade has a straight lower edge extending parallel to the foot plate and the openings 3 and 4 through which the axles for the rollers pass are all formed through the side walls of the pocket at an equal distance from the lower edges of the side walls, the rollers will all project the same distance out of the pocket and will all have engagement with the ground when the skate is in use. It should be further noted that the rollers are of such diameters that when they are rotatably mounted in the pocket they will project out of the pocket only a very short distance. Therefore, the rollers will be braced against side strain when skating and also a person's foot will only be raised above the ground a short distance. Therefore, there will be less danger of a person losing his balance and falling when skating. Each roller is formed with a centrally located opening 10 to receive its axle 5 and end portions of the opening are enlarged to form cups or bearing braces 11 in which are disposed bearing 100

balls 12. The balls are of slightly greater diameter than the depth of each cup and, therefore, when they are fitted into the cups in engagement with the walls thereof they will project slightly, as clearly shown in Figure 3, for engagement with the axle and with the inner faces of the side walls of the pocket. By this arrangement the rollers will be held out of engagement with the axles and the side walls of the pocket and permitted to turn very freely.

In order to secure the skate, there has been provided front straps 13 and a rear stirrup 14 to which are secured rear straps 15. The straps 13 are secured against the foot plate at opposite sides thereof by rivets or other equivalent fasteners 16 and one carries a buckle 17 so that the straps may be tightened across the toe of a person's shoe. Lower marginal portions of the stirrup 14 are folded to extend beneath the rear portion of the foot plate and secured by rivets 18. A buckle 19, similar to the buckle 17, is carried by one of the straps 15. Therefore, the straps 15 may be brought forwardly and secured about the ankle. I have, therefore, provided a roller skate which is simple in construction but at the same time very strong and durable and have further provided a skate having rollers rotatably mounted in an approved manner and so mounted that they may turn easily and be braced against side strain when the skates are in use.

Having thus described the invention, I claim:

1. A roller skate comprising a body having a longitudinally extending depending blade formed with a longitudinally extending pocket opening through its lower edge face and having side walls, rollers disposed in said pocket in spaced relation to each other longitudinally thereof and having their lower portions projecting out of the pocket, said rollers each having a central opening formed with enlarged end portions constituting bearing races and the walls of the pocket being formed with opposed openings, axles for said rollers engaged in the openings of the walls and passing through the openings in the rollers, and bearing balls in said races bearing against walls thereof and projecting therefrom and bearing against the axles.

2. A roller skate comprising a foot plate, a blade formed integral with the foot plate intermediate its width and projecting downwardly therefrom, said blade being formed with a longitudinally extending pocket extending for approximately its full length and having side and end walls, the side walls having opposed openings therein and the openings of one wall being of reduced diameter and threaded, rollers in said pocket having central openings alined with openings in the side walls, and axles passed through said rollers and each having one

end portion formed with a head bearing against the outer side face of one side wall and its other end reduced and threaded and engaged in a threaded opening of the second side wall, said axles rotatably mounting the rollers and the rollers having their lower portions projecting slightly from the pocket and terminating in a common horizontal plane.

In testimony whereof I affix my signature.
